United States Patent Office

Des. 197,531
Patented Feb. 18, 1964

197,531

DOOR HOOK OR SIMILAR ARTICLE

Leroy F. Hollenbeck, Jr., Miami Beach, Fla., assignor to
Perkins Marine Lamp and Hardware Corp., Miami
Beach, Fla., a corporation of Florida

Filed June 7, 1963, Ser. No. 75,268

Term of patent 14 years

(Cl. D50—5)

Fig. 1.

Fig. 2.

Fig. 3.

FIGURE 1 is a front elevational view of a door hook, or similar article, showing my new design;

I claim:

The ornamental design for a door hook or similar article, as shown.
